US00D759043S

(12) **United States Design Patent**
Cho

(10) **Patent No.:** **US D759,043 S**
(45) **Date of Patent:** **** Jun. 14, 2016**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventor: **Min-Kyung Cho**, Seoul (KR)

(73) Assignee: **Samsung Electronics Co., Ltd.,**
Suwon-si (KR)

(**) Term: **14 Years**

(21) Appl. No.: **29/476,229**

(22) Filed: **Dec. 12, 2013**

(30) **Foreign Application Priority Data**

Sep. 3, 2013 (KR) 30-2013-0045272

(51) **LOC (10) Cl.** **14-04**

(52) **U.S. Cl.**
USPC **D14/485**

(58) **Field of Classification Search**

USPC D14/485-495
CPC G06F 3/04815; G06F 3/04817; G06F
3/0483; G06F 3/0482; G06F 3/0484

(57) **CLAIM**

The ornamental design for a display screen or portion thereof with graphical user interface, as shown and described.

DESCRIPTION

The sole FIGURE is a front view of a display screen or portion thereof with graphical user interface, showing my new design. The broken lines are for illustrative purpose only and form no part of the claimed design. The dot-dash broken lines define boundaries of the claimed design and form no part thereof.

1 Claim, 1 Drawing Sheet
